CLAIM

We claim the ornamental design for the portable information handling system housing, as shown and described.

DESCRIPTION

FIG. 1 is a front perspective view of the portable information handling system housing comprising the present invention; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; and, FIG. 8 is a front perspective view thereof in an open position. Broken lines shown in the drawings illustrate portions of the portable information handling system housing, and form no part of the claimed design.
